UNITED STATES PATENT OFFICE.

ALFRED GEORGE BROWNING, OF SOUTH NORWOOD, LONDON, ENGLAND.

PUMP OR THE LIKE.

1,342,087.

Specification of Letters Patent.

Patented June 1, 1920.

Application filed November 13, 1919. Serial No. 337,761.

To all whom it may concern:

Be it known that I, ALFRED GEORGE BROWNING, a subject of the King of England, residing at South Norwood, London, 5 England, have invented certain new and useful Improvements in Pumps or the like, of which the following is a specification.

This invention is for improvements in or relating to pumps or the like and has for one 10 of its objects to provide an improved construction of piston or bucket pump wherein the sealing of the bucket is more effective than hitherto.

The primary feature of the present invention consists in the combination with a 15 piston and cylinder of projections on both such parts, each encircling the axis of the cylinder, one set of projections overlapping and sliding in the other set during the relative reciprocation of piston and cylinder. Conveniently one or more relief valves communicating with the spaces between the 20 projections are provided with the object of relieving them of any excessive pressure due to air or other fluid being trapped therein during the compression stroke. One or more 25 lubricant ducts are also preferably provided communicating with the spaces between the projections so that lubricant may 30 be introduced thereto.

According to another feature of the invention the piston has a conduit therethrough controlled at each end by a valve, one valve being mounted with its stem to 35 slide in the piston or piston rod and having a projection in or on which the stem of the second valve is mounted to slide, such projection serving as the sole guiding means for the stem of the second valve. By this 40 means an unobstructed throughway is provided. Conveniently, the valves, the valve seatings, or both, have their faces of extended dimensions to guide the valves into operative position.

According to a further feature of the invention two cylinders mounted side by side are connected together at one end to a single intake conduit and at the other end to a single delivery conduit, the latter preferably 45 including an air-cushion chamber opening into it.

For a more complete understanding of the invention there will now be described one constructional form of pump according to 50 the invention. It is to be understood that

this description is given by way of example only and that the constructional details enumerated may be modified in many respects without departing from the spirit and scope of the invention.

60

In the accompanying drawings:—

Figure 1 is an elevation of the pump partly in section, and

Fig. 2 is a fragmentary section on the line 2—2 of Fig. 1 on a larger scale than the 65 latter.

Like letters of reference indicate like parts throughout the drawings.

The pump comprises a framework or casting A into which the various detail parts 70 of the pump are built. Two cylinders B and C are mounted side by side and parallel to each other, their interiors being connected at the lower ends by conduits D to an intake aperture E fitted with a valve 75 seat E¹ and valve E² whereof the stem E³ is housed in a suitable guideway E⁴ and normally pressed downward by a spring E⁵. This valve E² will operate to maintain a certain amount of the fluid always in the 80 pump even though the latter be not operating at the moment. At their upper ends the cylinders are connected by conduits F to a delivery pipe G into which opens an air-cushion chamber H which will operate to 85 prevent undue shocks.

At their lower ends the cylinders are provided with annular projections J leaving between them annular spaces or channels to which lubricant may be introduced through 90 the ducts J¹ by removing the screws J². Within the cylinders B and C are buckets or pistons B¹ and C¹ respectively having piston rods B², C² connected by rods B³, C³ to cranks B⁴, C⁴ upon a main driving shaft 95 K, the cranks B⁴, C⁴ being set at an angle of 180° relatively to each other. In Fig. 1 both cranks are shown as horizontal, the crank B⁴ projecting forwardly and the crank C⁴ projecting rearwardly. The pistons B¹ and C¹ are each provided with an 100 annular projections L which overlap and slide in the projections J during the reciprocation of the pistons, being a good fit therewith. The projections L forms spaces or channels 105 which are provided with one or more relief valves L¹ communicating, say through conduits L², with each such space or channel. The valves L¹ are preferably spring-loaded and serve to relieve any excessive pressure 110

set up in the spaces with which they are connected. It will be seen that by reason of the inter-engaging projections on the piston and cylinder end fluid compressed by 5 the movement of the piston can only escape past the latter, when the piston valves hereinafter described are shut, by traversing the labyrinthine path up and down the sides of the annular projections. This method of 10 preventing leakage past the piston is found to be more efficient than providing piston rings in the outer circumference of the piston.

The pistons are each provided with a tubular valve seating B^5 , C^5 forming a conduit through the piston. Coöperating with the valve seating is a valve B^6 , C^6 whereof the stem is housed to slide in the piston or piston rod. These valves are each provided 20 with a projection B^7 , C^7 in or on which the stem B^8 , C^8 of another valve B^9 , C^9 is mounted to slide. Seatings D^1 are provided for the valves B^9 , C^9 and it will be seen that the valves B^9 , C^9 and the seatings D^1 , and 25 also the valves B^6 , C^6 have their faces of extended dimensions to guide the valves into operative position. This precaution is preferable since the projections B^7 , C^7 form the sole guiding means for the stems of the 30 valves B^9 , C^9 . It will be seen that the construction just described provides an unobstructed path for fluid through the piston when the valves B^6 , C^6 are open.

The parts are shown in Fig. 1 as being in 35 the position in which the piston B^1 is midway through its upstroke while the piston C^1 is midway through its downstroke. In moving upward the piston B^1 will lift the water or other fluid above it, under the 40 pressure of which the valve B^6 will shut. Owing to the pressure below the piston B^1 being thus reduced, water or other fluid in the conduit D will force the valve B^9 up and into the space between it and the valve 45 B^6 . On the downstroke of the piston B^1 the pressure on the valve B^9 will close it and force open the valve B^6 , the water or other fluid passing above the latter into position to be lifted during the next upstroke of the 50 piston. The operations of the piston C^1 and its valves are, of course, precisely the same but differently timed.

The invention has the advantage of simplicity and cheapness of construction and 55 the pump can be run at a very high speed without reduction in the efficiency. Any desired number of projections J and L may be employed according to the particular circumstances in which the pump is to be 60 used. Also, while the construction illustrated in the drawings is more particularly applicable for pumping water or other liquids, it will be understood that the invention may also be applied to pumps or ex- 65 hausters for air or other gases.

What I claim as my invention and desire to secure by Letters Patent is:—

1. In a pump or the like the combination with a piston and cylinder of projections on both such parts each encircling the axis of 70 the cylinder, one set of projections overlapping and sliding in the other set during the relative reciprocation of piston and cylinder and relief valves communicating with the spaces between the projections, for the 75 purpose specified.

2. In a pump or the like the combination with a piston and cylinder of projections on both such parts each encircling the axis of 80 the cylinder, one set of projections overlapping and sliding in the other set during the relative reciprocation of piston and cylinder and a relief valve communicating with each of the spaces between the projections, for the purpose specified. 85

3. In a pump or the like the combination with a piston and cylinder of projections on both such parts, each encircling the axis of the cylinder, one set of projections overlapping and sliding in the other set during the 90 relative reciprocation of piston and cylinder and lubricant ducts communicating with the spaces between the projections, for the purpose specified.

4. In a pump or the like the combination 95 with a piston and cylinder of projections on both such parts each encircling the axis of the cylinder, one set of projections overlapping and sliding in the other set during the relative reciprocation of piston and cylinder and a lubricant duct communicating 100 with each of the spaces between the projections for the purpose specified.

5. In a pump or the like the combination with a piston and cylinder of projections 105 on both such parts each encircling the axis of the cylinder, one set of projections overlapping and sliding in the other set during the relative reciprocation of piston and cylinder, a conduit through the piston, a valve 110 controlling each end of such conduit and stems on said valves, one valve being mounted with its stem to slide in the piston and having a projection relatively to which the stem of the second valve slides, such projection 115 serving as the sole guiding means for the stem of the second valve, for the purpose specified.

6. In a pump or the like the combination with a piston and cylinder of projections on 120 both such parts each encircling the axis of the cylinder, one set of projections overlapping and sliding in the other set during the relative reciprocation of piston and cylinder, a conduit through the piston, a valve 125 controlling each end of such conduit such valves having their operative faces of extended dimensions to guide the valves into operative position and stems on said valves, one valve being mounted with its stem to 130

slide in the piston and having a projection relatively to which the stem of the second valve slides, such projection serving as the sole guiding means for the stem of the second valve, for the purpose specified.

7. In a pump or the like the combination with a piston and cylinder of projections on both such parts each encircling the axis of the cylinder, one set of projections overlapping and sliding in the other set during the relative reciprocation of piston and cylinder, a conduit through the piston, a valve controlling each end of such conduit, valve seatings for the valves, such seatings having their operative faces of extended dimensions to guide the valve into operative position and stems on said valves, one valve being mounted with its stem to slide in the piston and having a projection relatively to which the stem of the second valve slides, such projection serving as the sole guiding means for the stem of the second valve, for the purpose specified.

8. In a pump or the like the combination with a piston and cylinder of projections on both such parts each encircling the axis of the cylinder, one set of projections overlapping and sliding in the other set during the relative reciprocation of piston and cylinder, a conduit through the piston, a valve controlling each end of such conduit, such valves having their operative faces of extended dimensions to guide the valves into operative position, valve seatings for the valves, such seatings having their operative faces also of extended dimensions to guide the valves into the operative position and stems on said valves, one valve being mounted with its stem to slide in the piston and having a projection relatively to which the stem of the second valve slides, such projection serving as the sole guiding means for the stem of the second valve, for the purpose specified.

45 9. A pump or the like comprising in combination two cylinders mounted side by side, a single intake conduit connected to one end of both cylinders, a single delivery conduit connected to the other end of both cylinders, a piston in each cylinder, coöperating sets of projections on each related piston and cylinder, such projections each encircling an axis of a cylinder, and in each related piston and cylinder one set of projections overlapping and sliding in the other set during the relative reciprocation of piston and cylinder, and relief valves communicating with

the spaces between the projections for the purpose specified.

10. A pump or the like comprising in combination two cylinders mounted side by side, a single intake conduit connected to one end of both cylinders, a single delivery conduit connected to the other end of both cylinders, an air-cushion chamber opening into the delivery conduit, a piston in each cylinder, coöperating sets of projections on each related piston and cylinder, such projections each encircling an axis of a cylinder, and in each related piston and cylinder one set of projections overlapping and sliding in the other set during the relative reciprocation of piston and cylinder, and relief valves communicating with the spaces between the projections for the purpose specified. 75

11. A pump or the like comprising in combination two cylinders mounted side by side, a single intake conduit connected to one end of both cylinders, a non-return valve in such intake, a single delivery conduit 80 connected to the other end of both cylinders, an air-cushion chamber opening into the delivery conduit, a piston in each cylinder, coöperating sets of projections on each related piston and cylinder, such projections 85 each encircling an axis of a cylinder, and in each related piston and cylinder one set of projections overlapping and sliding in the other set during the relative reciprocation of piston and cylinder, and relief valves communicating with the spaces between the projections for the purpose specified. 90

12. A pump or the like comprising in combination two cylinders mounted side by side, a single intake conduit connected 95 to one end of both cylinders, a non-return valve in such intake having its operative faces of extended dimensions to guide it into operative position, a single delivery conduit connected to the other end of both 100 cylinders, an air-cushion chamber opening into the delivery conduit, a piston in each cylinder, coöperating sets of projections on each related piston and cylinder, such projections each encircling an axis of a cylinder, and in each related piston and cylinder one set of projections overlapping and sliding in the other set during the relative reciprocation of piston and cylinder, and relief valves communicating with the spaces 105 110 between the projections for the purpose specified.

In testimony whereof I affix my signature.
ALFRED GEORGE BROWNING.
